UNITED STATES PATENT OFFICE.

ULYSSES G. KNAUFF, OF MINNEAPOLIS, MINNESOTA.

HYDROCARBON BURNER.

Application filed July 1, 1922. Serial No. 572,282.

To all whom it may concern:

Be it known that I, ULYSSES G. KNAUFF, a citizen of the United States, residing at Minneapolis, in the county of Hennepin and 5 State of Minnesota, have invented certain new and useful Improvements in Hydrocarbon Burners; and I do hereby declare the following to be a full, clear, and exact description of the invention, such as will enable others skilled in the art to which it 10 appertains to make and use the same.

My invention provides an extremely simple and highly efficient hydro-carbon burner especially adapted for use in hot 15 water and steam boilers and in furnaces such as used in domestic heating plants, but the burner is, nevertheless, capable of more general use.

Generally stated, the invention consists of 20 the novel devices and combinations of devices hereinafter described and defined in the claims.

In practice, I have found that an efficient burner for fluid hydro-carbon fuels, such as 25 kerosene, distillate and even crude oil, must be arranged for the concentric delivery of the fluid fuel and the air and that there must be a free end even clearance for the escape of the flames from the burner in all 30 directions radially outward from the axis of the burner. I have also found that the combustion may be rendered more complete and more effective when a proper limited amount of water vapor is commingled with 35 the air prior to the delivery of the air into the flame or into a mixture with the hydro-carbon vapor.

My invention provides a burner having all 40 of the above noted and other desirable characteristics. The preferred form of the improved burner is illustrated in the accompanying drawings, wherein like characters indicate like parts throughout the several views.

Referring to the drawings:

Fig. 1 is a view partly in side elevation but with some parts sectioned and with some parts broken away, showing the improved burner installed within a hot water 50 heater or burner; and

Fig. 2 is an enlarged plan view of the burner removed from the boiler or heater, some parts thereof being broken away.

The numeral 3 indicates a hot water heater 55 or boiler having the customary grate 4, fuel door 5, ash pit 6 and ash door 7.

The improved burner comprises a heavy disk-like deflecting base 8 that is placed centrally on the grate 4 and is formed in its upper surface with a depressed annular 60 basin 9, at the center of which is a raised apex 10, through which latter the fuel delivery pipe 11 extends upward to a point slightly above the same. This pipe 11 extends from a suitable source of fluid fuel 65 supply, such as an elevated tank, not shown, and said pipe is provided with a valve 12, by means of which the flow of the fluid fuel may be controlled or cut off, at will.

Concentrically located above the base 8 70 is a cylindrical dome 13, the lower edge of which is spaced above the basin 9, preferably by bearing lugs 14 formed on said base.

A large air intake pipe 15 taps an axial 75 hole in the top of the dome 13 and is extended therefrom, first rearward and then downward through the rear of the grate 4 and thence out through the ash pit 6, and terminates just outside of the front of said 80 ash pit. As shown, the pipe 15 is made up of sections and, for connection to the dome, it is flanged at 16. Located within the dome 13 and having an axial passage aligned with the axial passage of the top 85 of said dome is a small annular water trough 17, through the flanged upper edge of which and the flange 16 are passed nut-equipped bolts 18 to rigidly connect the said elements 13, 15 and 17. The upturned outer flange 90 of the water trough 17 is spaced from the sides and top of the dome and water is supplied thereto through a small water pipe 19. In this preferred arrangement, the 95 water pipe 19 extends from a suitably supported elevated tank 20, the top of which is normally closed and made air-tight by a plug 21. Said tank is shown as supported from the heater by brackets 22, but it may be supported in any suitable way. The pipe 100 19 is provided with a regulating valve 33 and it is extended inward, thence upward and thence downward through the air intake pipe 15 and, at its delivery end, taps the trough 17 at a point materially below the 105 upper edge of the outer flange of said trough. With this arrangement, the water will not be heated while in the pipe 19 and, hence, scale will not be formed within said pipe. When the water reaches the vapor 110 pan 17, it will be subjected to heat and will be vaporized so that it will commingle with

the air drawn into the dome 13 through the air pipe 15. The air will be brought to a high temperature within the dome and will be commingled with the hot vapors 5 and the two will be commingled with the hydro-carbon vapors generated on the base 8 and within the annular basin 9.

In starting the burner into action, a small amount of gasoline may be poured into the 10 basin 9, but after the burner is in action, the base 8 will be kept so hot that the oil or hydro-carbon fluid, slowly running into the basin 9, will be quickly generated into vapor form.

15 Surrounding the base 8, the grate 4 should be covered with ashes, cement or other substance so that all of the air that can be drawn into the combustion chamber of the furnace must come in through the air pipe 20 15. This will produce a strong down-draught through the dome so that the air and water vapor, not commingled with the hydro-carbon vapor, will be evenly drawn 25 radially outward in all directions and thoroughly commingled with said hydro-carbon vapor so that an even flame will be produced in all directions around and outward from the dome. These flames will also be directed 30 outward and against the surrounding side walls of the heater or boiler. Inasmuch as the top of the water tank is closed and the delivery end of the pipe 19 is below the top of the outer flange of the water or vapor trough 17, it follows that water to a predetermined level will be maintained in said 35 trough because the flow of water will be automatically stopped whenever the water covers the delivery end of said pipe and will be automatically started whenever the water falls low enough to open up the delivery 40 end of the said pipe.

In actual practice, this improved burner has been found highly efficient for the purposes had in view.

45 What I claim is:

1. A burner of the kind described comprising a base having an annular basin, a

fluid fuel supply pipe extended centrally through said base for discharge into said basin, a dome concentrically located over but 50 spaced from said basin, an air intake pipe centrally connected to the top of said dome, an annular water trough concentrically located in the upper portion of said dome around the intake air pipe thereof, and a 55 water supply pipe leading to said trough.

2. The structure defined in claim 1 in which said water pipe extends to said water trough through said air intake pipe.

3. The structure defined in claim 2 in 60 which the delivery end of said water pipe is below the top of said trough, and in further combination with a closed elevated water supply tank connected to the other end of said water pipe.

65 4. A burner of the kind described comprising a metallic base having an annular basin, an approximately cylindrical dome concentrically spaced above said basin and having an axial air intake passage in its top, 70 an air intake tube having a flanged delivery end aligned with the air intake passage in the top of said dome, an annular water pan having a flanged central portion aligned with the air intake passage in the top of 75 said dome, and bolts passed through the top of said dome and the flanges of said air intake passage and water trough and detachably but rigidly connecting said dome, air intake passage and pan.

80 5. The structure defined in claim 4 in combination with a water supply pipe extended through the air intake pipe and connected to said annular trough below the top thereof.

85 6. A heater having a combustion chamber, a fuel intake door, a grate and an ash pit, in combination with the structure defined in claim 3 in which said air intake pipe and water pipe extend from said dome rearward, thence downward through said grate and thence forward through said ash pit.

90 In testimony whereof I affix my signature
ULYSSES G. KNAUFF.
